UNITED STATES PATENT OFFICE.

VICTOR B. ADAMS, OF CINCINNATI, OHIO, AND GEORGE J. SCHALLER, OF COVINGTON, KENTUCKY.

SOAP-HOLDER FOR WASHBOARDS.

No. 901,768.

Specification of Letters Patent.

Patented Oct. 20, 1908.

Application filed August 3, 1908. Serial No. 446,782.

To all whom it may concern:

Be it known that we, VICTOR B. ADAMS and GEORGE J. SCHALLER, citizens of the United States, and residents, respectively, 5 of Cincinnati, Hamilton county, State of Ohio, and Covington, Kenton county, and State of Kentucky, have invented certain new and useful Improvements in Soap-Holders for Washboards, of which the following is a specification.

This invention relates to wash-boards that have a soap-holder attachment at the upper end of the rubbing portion thereof and the object is to supply a device that is readily 15 adapted to be attached to the upper portion of the wash-board and to hold the bar of soap so as to present and feed it outwardly in an opening adjacent to the upper end of the rubbing-surface and, also, to provide simple 20 means whereby the user of the board can readily and minutely advance the said held bar of soap for duly soaping the clothes while in the washing operation on such clothes and without necessity of using either hand 25 to handle the soap.

The invention consists in the provision in connection with a wash-board having upright stiles or side legs and a suitable rubbing-surface intervening and carried by said side- 30 stiles, of a main filling-plate secured at its opposite ends to upper extensions of said side-stiles and having an elongated central opening therein adjacent the upper end of said rubbing-surface, a slotted guide-way on the back of said filling plate registering with said elongated opening therein, a carrier-plate having a flat bar and a pair of rear, inclined wedge faces and mounted in said guide-way for transverse movement thereacross, a soap- 35 holding plate intermediate the carrier-plate and the orificed portion of said filling-plate, a thumb-screw whose shank is passed through a slot or an elongated opening in the upper extension of one of said side-stiles, a travel- 40 ing-nut on said thumb-screw and a slotted box at one end of the flat bar of said carrier, the said traveling-nut being inclosed within said box and adapted to carry or reciprocate said carrier plate transversely along said 45 guide-way and the said tapering formations on the back of said carrier plate being adapted to move the said soap-holding plate forward and thereby project the bar of soap the desired distance beyond the face of the first-

named filling plate in the progress of the 55 clothes washing.

All the features of the invention herein will be fully hereinafter described and particularly pointed out in the claims.

In the accompanying sheet of drawings, 60 Figure 1 is a front elevation of a wash-board embodying our invention; Fig. 2, a fragmentary, sectional elevation, taken on the dotted-line *a*, *a*, of Fig. 3, showing our improvement as it appears in use, with the soap 65 very slightly projected beyond the face of the main filling-plate that closes the upper portion of the wash-board between the upper extensions of the side-stiles; Fig. 3, a fragmentary elevation showing the rear face of 70 the upper portion of the wash-board, with our improvement clearly indicated therein; Fig. 4, a transverse section taken on the dotted-line *b*, *b*, of Fig. 3, but on a somewhat larger scale and showing our device in opera- 75 tive position ready for the soaping of the clothes to be washed; and Fig. 5, a front elevation of the soap-holding back-plate adapted for use immediately back of the feed orifice in the filling-plate.

In these views, 1 and 2 respectively represent the upright side-stiles or side legs of a wash-board, and 3 the rubbing-surface supported by said side-stiles and laid, as customary, over a back-board 4. The rubbing- 85 surface is shown as being made of corrugated material in the ordinary form long in use, but it is obvious that any suitable form of rubbing-surface may be used in the wash-board as that is not material to the essential feature of our invention herein and constitutes no part of such invention excepting, as a matter of course, the part it takes in the washing of the clothes after the soaping thereof.

1^a and 2^a respectively indicate the customary upper extensions of the side-stiles, their extreme upper ends being connected by a transverse top-bar 5 in the usual manner, and a transverse bottom-bar 6 is provided in 100 the wash-board at the top of the rubbing-surface 3, as best seen in Fig. 2, in a like usual manner.

The upper extensions 1^a and 2^a and the transverse bars 5 and 6 form the usual soap- 105 carrying receptacle of a wash-board, but in the use of the ordinary wash-board a wooden filling-board or back is inserted in the open-

ing between said extensions and transverse bars. In the application of our device herein, we prefer to discard said wooden filling-board and use instead a metal filling-plate 7 whose opposite ends 7^a are flanged and bent over so that the body portion of the plate may set back within the opening and on a suitable vertical plane with the upper rubbing-edges of said rubbing-surface 3 and to provide for the attaching screws or nails 7^b, all as best seen in Fig. 2.

An elongated, rectangular opening or orifice 8 is provided in the lower central portion of the filling-plate 7, with its lower edge adjacent the upper edge of said rubbing-surface 3 and a guide-way is provided on the back of said plate 7, registering with said orifice 8. Said guide-way is composed of a raised frame 9 having an elongated opening 9^a, longitudinal feet 9^b being provided along the opposite upper and lower edges of such frame and accommodating rivets 9^c whereby the guide-way is secured to the back of the plate 7. A back-plate 8^a is provided to the rear of orifice 8 and has vertically-projecting corners 8^b to fit freely against the opposite end walls of the raised frame 9 of the guide-way, so that it may move to and from the orifice 8, as hereinafter referred to.

30 A soap-carrier frame is provided in the guide-way back of plate 8^a and the orifice 8 and is composed of a flat bar or thin strip of sheet-metal forming a carrier-plate 10 whose longitudinal side edges have a slide-fit in said guide-way, and a pair of tapered members 11, 11^a, are provided on the back of said carrier-plate 10 to form wedge or forwardly-projecting means on the carrier for advancing said carrier and back-plate 8^a toward the main filling-plate 7. An extension 12 is provided at one end of the carrier-plate 10 and carries on its rear side an open box 13 having elongated openings or slots 14 in its two walls or sides, as best seen in Fig. 4.

45 15 indicates the threaded shank of a thumb-screw, 15^a indicating the handle at the outer end thereof, and 16 a nut on said threaded shank, the latter passing through the slots 14 in the box 13 of the carrier and said nut 16 being located on the said shank between the sides or walls of said box 13, so that when the thumb-screw is turned in either direction, it (said nut) will travel along said threaded shank and reciprocate the carrier in its guide-way back of the soap opening or orifice 8. A horizontally-elongated opening 15^b is made in the upper extension 1^a of the side-stile 1, to suitably accommodate the thumb-screw 15 and allow a pivotal movement of said thumb-screw on its bearing-washer 17 to compensate for the allowance made for the movement of said screw-shank in the slots 14 of the traveling-nut box 13 and for the forwardly-projecting or advancing and retreating movements of the soap-

carrier devices to and from the orifice 8 in the filling-plate 7, all as will be readily understood, especially by reference to the structure seen in Fig. 4.

An opening or slot 11^b and a notch 11^c are provided in the wedge-member 11^a and the guide-frame 9, respectively, to allow for the pivotal movement of the inner end of the shank of the thumb-screw 15 in reciprocating the soap-carrier across the orifice 8. A nut 16^a is provided on the screw 15 adjacent the inner end of the opening 15^b and is held from reciprocating or traveling along the screw by means of a transverse pin 16^b, passed through the nut and screw. This nut prevents the undue pulling of the carrier-frame across its guide-way independent of the nut 16.

In the operation of our device, a bar of soap x is placed against the face of back-plate 8^a within the orifice 8, after the carrier has been duly retreated a suitable distance backward for the outer face of the soap to project but very slightly beyond the plane or outer face of the filling-plate 7, as best seen in Figs. 2 and 4. The bar of soap is preferably moistened before placing against the back-plate 8^a in said orifice, so that its inner face shall somewhat stick and at the same time the sliding of the carrier plate along the rear face of back-plate 8^a is effected 95 or permitted, which will be readily understood. In soaping the clothes, they are taken from the water, piece by piece, as usual, and rubbed over the outer face of the bar of soap and then rubbed as usual over 100 the corrugated surface 3 and then easily re-soaped, if necessary, in a like manner and without the operator handling or touching the soap, or without putting such soap in the water below as is customarily the case in the 105 use of wash-boards having the ordinary soap-receptacle at the top of the board from whence it may be accidentally displaced and wholly subjected to a flushing of water to unduly waste it. As the slightly projecting face of 110 the soap wears away in the washing of the clothes, the bar or cake is very easily projected outwardly, as the wash progresses, by simply turning the thumb-screw 15 whose pitch is such that even the slightest part of 115 the bar may be made to project beyond the orifice 8, or even put on the same plane as that of the outer face of the filling-plate 7, or sufficient to suit the kind of clothes being washed, some clothes taking a greater 120 amount of soap than others, and some that are more soiled than others taking a correspondingly greater amount each time they are soaped, and our device being especially adapted to suit the condition and character 125 of the clothes, as is very clearly obvious. It will be seen, in Fig. 4, that the side edges of the orifice 8 are turned or bent over inwardly and rounded slightly, thereby forming a suitable wall at either side to prevent the soap 130

itself becoming cut into or indented, or sliding under or back of the said filling-plate 7, laterally away from the orifice 8. Spacing-blocks 18 are provided on the backs of the 5 side-stiles to rest the board upon the edge of the tub and permit free movement of the wedges 11 and 11^a.

We claim:—

1. A soap-holder for a wash-board, comprising a plate having an elongated opening or orifice, a guide-way on the back of said plate and coinciding with said orifice, a carrier-plate in said guide-way, tapering means carried by said carrier-plate and 10 adapted to forwardly-project said carrier-plate toward said orifice, and means for reciprocating said carrier-plate across the rear of said orifice.
2. A soap-holder for wash-boards, comprising a filling-plate having an orifice for the soap therein, a raised and orificed guide-frame mounted on the rear face of said filling-plate registering with said soap-orifice, a carrier-plate engaging said guide-way and 15 having thereon a pair of inclined or tapered members adapted to engage said guide-way and forwardly-project said carrier toward

said soap-orifice, a slotted box at the fore end of said carrier, a thumb-screw having a traveling-nut thereon and adapted to engage 30 within said slotted box to propel or reciprocate said soap-projecting carrier and a suitable frame for supporting the device above a rubbing-surface.

3. A soap-holder for wash-boards, comprising a filling-plate having an orifice for the soap therein, a rearwardly and forwardly movable back-plate in said orifice, a raised and orificed guide-frame mounted on the rear face of said filling-plate registering with 35 said soap-orifice and back-plate, a carrier-plate engaging said guide-way and having thereon a pair of tapered members or wedges adapted to engage said guide-way and forwardly-project said carrier and back-plate 40 toward said soap-orifice, and means for reciprocating said carrier-plate across said guide-way. 45
